ASH REMOVER

William A. Biddell, Frederick, Md., assignor to
The General Engineering Company, Frederick,
Md., a corporation of Maryland

Application December 14, 1944, Serial No. 568,158

7 Claims. (Cl. 302—50)

This invention relates to ash disposal apparatus for stokers or other coal burning equipment, and the main object is to provide means of a novel, efficient, and practical nature for removing the ashes from the retort or burning zone and conveying them to a remote point where they may be emptied into a suitable receptacle or otherwise disposed of.

A further object is to provide an ash removal mechanism that includes mechanical and pneumatic means with automatic control for the air conveyance whereby the latter will only be operated intermittently and for such periods as may actually be required.

Still other and more specific objects will be set forth in the following specification, reference being had to the accompanying drawings, wherein:

Fig. 1 is a side elevation of a stoker-burner equipped with my improved ash remover, a portion of the coal tube being broken away for purpose of illustration.

Fig. 2 is a top or plan view of the stoker equipment shown in Fig. 1.

Fig. 3 is an enlarged detail elevation of the fan or blower assembly used in the ash conveyor, and with the cover plate of the control switch box broken away.

Fig. 4 is an enlarged sectional elevation on line 4—4 in Fig. 2.

Fig. 5 is a side elevation showing a modified form of the device.

Fig. 6 is a plan view of the construction shown in Fig. 5, but with fractional portions broken away.

Fig. 7 is a sectional elevation on line 7—7 in Fig. 5.

Fig. 8 is a sectional elevation on line 8—8 in Fig. 5.

Referring to the drawings more particularly and by reference characters A designates the retort of a stoker, which also includes a hopper B, coal screw or supply tube C connecting the retort and hopper, and air supply duct D, all of common and well known construction.

Suitably connected with the retort A is a pipe section 10 adapted at one end to receive ashes from the retort and guide them into the tubular chamber 11 of a housing unit 12. A feed auger 13 is located in the conduit 10 and chamber 11, and this auger has a shaft 14 which extends through a cap 15 in one end of the chamber 11 and to a suitable driving motor or mechanism (not shown) by which it may be constantly driven at comparatively slow speed when the stoker

is operating. This auger is rotated to feed in the direction of the arrows in Fig. 4, so as to convey the ashes to a point below an opening 16 in the chamber 11. It may here be noted that the auger is provided, beyond the discharge opening 16, with a reverse screw or flight 17, the purpose of which is to cooperate with the main auger to squeeze or push the ashes up into and through the opening 16.

10 Above the opening 16 the casing 12 is provided with a passageway 18, one end of which connects with the discharge 19 of a blower fan 20, and the other end of which attaches to a pipe 21 through which the ashes are conducted to their 15 destination. The fan 20 operates in housing 22 on which is mounted an electric motor 23, for driving the fan.

Within the passage 18, and directly above the opening 16, is located a tiltable, normally inclined 20 plate 24 which is mounted on a rod or shaft 25 that extends through one wall of the housing 12 and into a chamber 26 where it supports a similarly inclined plate 27 (Fig. 3). Upon this plate 27 is mounted a mercury switch 28 which controls an electric circuit having wires passing through a cable or conduit 29 to the fan motor 23. A time switch 30 may also be included in the circuit and is of such nature that when the circuit has been closed by the switch 28 30 it will remain closed to energize the motor for a predetermined period of time even though the plate 24 may drop to open the switch 28. The purpose of this arrangement is to prevent starting and stopping of the blower motor for each 35 fluctuation of the plate 24, as that is unnecessary for successful operation.

It will be understood that as the ashes conveyed by the auger 13 are pushed up through the opening 16 they will raise the plate 24 and 40 when it reaches a predetermined height or level the switch 28 closes the fan motor to create a blast of air through the passageway 18 that will carry the ashes on through and up into the conduit 21 for disposal at a remote point. It will 45 further be understood that the plate 24 is not of such width or size as to close off the passageway 18, even when the plate is in its down position, and that as long as the fan is operating it will continue to force the air through to pick up and 50 carry away all the ashes within the passage and may even pick up considerable from within the opening 16.

In order to insure proper and most efficient operation of the air flow, and to prevent any possible 55 clogging of the passageway 18, I consider it

advisable to increase the velocity of the air stream at the initial point of contact with the ash body, and for that reason have provided an inclined plate 31 immediately in advance of the opening 16 to restrict the passageway and cause a Venturi action of the air as it passes over the opening 16. This plate 31 is mounted upon a rod or shaft 32 that extends to the exterior of the housing 12 and is there secured in an arm 33 which is arcuately adjustable so that the angle of the plate may be regulated. The arm 33 may be secured in the desired position by having a pull pin 34 selectively engageable with holes 35 in a lug projection 36 of the housing 12.

Referring now to the modified form of structure shown in Figs. 5-8, inclusive, 37 designates the ash tube or conduit through which the ashes are moved by an auger 38 toward an opening 39 which in this case extends from one side of the tube rather than upwardly as in the form first described. In this case too the auger has a reversed flight 40 which is spaced from the terminal end of the main auger and both screw sections are mounted on a common shaft 41, as in the previous instance.

It will be noted that the opening 39 permits the ashes to be pushed out into the chamber 42 of a casing 43 and in this chamber there is mounted an inclined plate 44 that is mounted on a rod, or shaft 45. This shaft extends to the exterior of the casing and at its outer end is provided with an arm 46 upon which is mounted a mercury switch 47 that controls the circuit to a motor 48 for a fan 49 mounted in a fan housing 50. The outlet of the fan connects with a conduit 51 which opens laterally into the chamber 42, and at the opposite side of the casing 43 there is provided a discharge or exhaust pipe 52 through which the ashes are carried to their ultimate destination. In this case too there is provided an air flow restricting plate (not shown) similar to the plate 31 and its angle is regulated by a control arm 53 that is adjustable in the same manner as the control arm 33 previously described.

In this modified form of the invention the ashes are pushed out into the chamber 42 until they build up to raise the plate 44 to a predetermined angle, at which time the mercury switch 47 operates to close the circuit to the motor 48 and thus start rotation of the fan 49. As the air is then discharged from the housing 50 it flows down into and through the conduit 51 and passes through the chamber 42 crosswise with respect to the plate 44 and thus picks up and carries with it the ashes which have accumulated in the chamber 42. The fan continues to operate for such period of time as may be necessary to clean out the chamber 42 after which it remains idle until sufficient ash material accumulates to again raise the plate 44 to repeat the process. In this case too the shaft 41 will be continuously operated in order to insure the continuous removal of all ashes from the retort and particularly so since little power is required to operate the auger. It may be explained, however, that in most stokers the volume of ash material to be removed is comparatively small and it is therefore not necessary or desirable to operate the fan except at infrequent intervals, and only at such times as enough ashes have accumulated to justify their removal.

It will further be understood that various other modifications may be made in the device as herein shown providing such modifications come within the spirit and scope of the appended claims. Having now therefore fully illustrated

and described preferred embodiments of my invention, what I claim to be new and desire to protect by Letters Patent is:

1. In an ash remover, an air conduit having an ash receiving port, a fan for blowing air through the conduit, a motor for the fan, and circuit control means for the motor including an element mounted adjacent said port for actuation by a predetermined accumulation of ash material passing into the passageway from the port, said passageway being provided with means in advance of the port to restrict the air opening and increase the air flow velocity as it traverses the port opening.
2. In an ash remover, an air conduit having an ash receiving port, a fan for blowing air through the conduit, a motor for the fan, and circuit control means for the motor including an element mounted in the passageway adjacent said port for actuation by a predetermined amount of ash material accumulated in the passageway, said passageway being provided with means in advance of the port to restrict the air opening and increase the air flow velocity as it traverses the port opening, and means for adjusting said restricting means to control the air velocity past the port opening.
3. In an ash remover, an ash conduit adapted to receive ashes from a retort or the like, an auger operating in the conduit to move the ashes therethrough, an air passageway disposed adjacent the discharge end of the conduit and communicating therewith through a connecting opening, a blower for blowing air through the passageway, a motor for operating the blower, and means actuated by a predetermined volume of ash material passing into the passageway from the opening for closing a circuit to the motor.
4. In an ash remover, an ash conduit adapted to receive ashes from a retort or the like, an auger operating in the conduit to move the ashes therethrough, an air passageway disposed adjacent the discharge end of the conduit and communicating therewith through a connecting opening, a blower for blowing air through the passageway, a motor for operating the blower, and means responsive to the accumulation of a predetermined amount of ash material in the passageway for closing a circuit to the motor, such motor circuit including a time switch adapted to maintain operation of the motor for a predetermined period of time irrespective of the position of said circuit closing means.
5. In an ash remover, an ash conduit adapted to receive ashes from a retort or the like, an auger operating in the conduit to move the ashes therethrough, an air passageway disposed adjacent the discharge end of the conduit and communicating therewith through a connecting opening, a blower for blowing air through the passageway, a motor for operating the blower, and means actuated by a predetermined volume of ash material passing into the passageway from the opening for closing a circuit to the motor, said connecting opening being above the auger, and said ash actuating means including a tiltable member overlying said opening.
6. In an ash remover, an ash conduit, an auger operating in said conduit, said conduit having a side port, adjacent the discharge end of the auger, opening into a chamber adapted to receive ashes under the delivery action of the auger, a tiltable member arranged in the chamber to be influenced by a predetermined accumulation of ash material delivered therein to, a switch oper-

ated by the tilttable member, said chamber having openings through which an air current may pass to carry away the ashes, a motor driven fan for creating such air current, and the motor for said fan being in circuit connection with said switch.

7. In an ash remover, an ash conduit, an auger operating in said conduit, said conduit having a side port, adjacent the discharge end of the auger, opening into a chamber adapted to receive ashes under the delivery action of the auger, a tilttable member arranged in the chamber to be influenced by a predetermined accumula-

tion of ash material delivered therein to, a switch operated by the tilttable member, said chamber having openings through which an air current may pass to carry away the ashes, a motor driven fan for creating such air current, and the motor for said fan being in circuit connection with said switch, said chamber openings being so arranged that the air flow through the chamber will be in a direction edgewise and crossways with respect to the tilttable member.

WILLIAM A. RIDDELL.
